UNITED STATES PATENT OFFICE.

WILLIAM E. CRAWFORD, OF DEVILS LAKE, NORTH DAKOTA.

SPRING-WHEEL.

1,216,082.

Specification of Letters Patent. Patented Feb. 13, 1917.

Application filed September 24, 1915. Serial No. 52,447.

To all whom it may concern:

Be it known that I, WILLIAM E. CRAWFORD, a citizen of the United States, residing at Devils Lake, in the county of Ramsey and 5 State of North Dakota, have invented certain new and useful Improvements in Spring-Wheels; and I do hereby declare the following to be a full, clear, and exact description of the invention, such as will enable others skilled in the art to which it 10 pertains to make and use the same.

This invention relates to spring wheels, and has for its object to provide a simple and efficient spring wheel especially designed 15 for use in connection with motor vehicles.

With this and other objects in view, the invention consists in the novel construction, arrangement and formation of parts as will be hereinafter specifically described, claimed 20 and illustrated in the accompanying drawings, in which:

Figure 1 represents a fragmental side elevation of the wheel, the adjacent hub-carried plate removed and parts being shown 25 in section.

Fig. 2 represents a fragmental sectional view through the spring wheel.

Fig. 3 represents a detail perspective view 30 of one of the spring actuated shoes removed, and

Fig. 4 represents an enlarged detail perspective view of one of the spacing springs for the shoes removed.

Referring to the drawings in detail, 35 wherein similar reference numerals designate corresponding parts, the numeral 5 indicates a hub of the usual or any preferred construction having an integral annular flange 6 formed adjacent its inner end. The 40 opposite end of the hub 5 is externally screwthreaded and receives a centrally apertured plate 7, which latter is secured in position upon the hub by a nut 8.

A pair of spaced plates 9 are arranged 45 between and in sliding contact with the inner surfaces of the flange 6 and outer removable plate 7 and are formed with central apertures 10 of considerably greater diameter than the internal diameter of the hub 5.

50 A spacing ring 11 is secured between the plates 9 inwardly of the circumferential

edges of the latter and a plurality of radiating wheel spokes 12 are secured between the plates 9 outwardly of the rim 11 by rivets 13, or other suitable means. 55

The hub 5 is formed centrally with a plurality of radiating arms 14, which terminate in spaced relation to the ring 11. The outer extremities of the arms 14 are slidably received within apertures 15 formed centrally 60 in inwardly directed sockets 16^a carried by the shoes 16, having the outer surfaces 17 suitably curved to snugly fit the inner surface of the ring 11. Springs 18 are coiled about the arms 14, engaged between the hub 65 5 and the sockets 16^a for normally retaining the ring 11 and plates 9 in concentrically spaced relation to the hub 5.

The sliding movement of the shoes 16 with relation to the ring 11 is limited by a 70 plurality of enlargements 19 formed internally of said ring. The shoes 16 are normally retained in uniformly spaced relation by V-shaped springs 20, having oppositely directed ends 21 engaged within recesses 22 75 formed in the side edges of the shoes 17.

What I claim is:

1. A spring wheel including a hub, a pair of spaced plates movable relatively to said hub, spokes radiating from said plates, a 80 ring secured between said plates, arms radiating from said hub, sockets slidably receiving the outer terminals of said arms, shoes carried by the outer terminals of said sockets and engaged with the inner surface 85 of said ring, springs interposed between said hub and said ring for normally retaining the latter in spaced relation to said hub, internal enlargements formed in said ring constituting stops for limiting the sliding movement of said shoes, and a plurality of springs 90 interposed between and connecting the adjacent ends of the shoes to normally retain the latter in uniformly spaced relation.

2. A spring wheel including a hub, a pair 95 of spaced plates movable relatively to said hub, spokes radiating from said plates, a ring secured between said plates, arms radiating from said hub, sockets slidably receiving the outer terminals of said arms, 100 shoes carried by the outer terminals of said sockets slidably engaged with the in-

ner surface of said ring, internal enlargements formed in said ring constituting stops for said shoes, springs interposed between the hub and said ring for normally retaining the latter in concentrically spaced relation to said hub, said shoes having their opposed side edges recessed, and substantially V-shaped leaf springs having outwardly directed ends engaged in said recesses for nor-

mally retaining said shoes in uniformly 10 spaced relation.

In testimony whereof I affix my signature in presence of two witnesses.

WILLIAM E. CRAWFORD.
